UNITED STATES PATENT OFFICE

WILLIAM P. DENNY, OF HOUSTON, TEXAS, ASSIGNOR OF ONE-HALF TO L. C. CHRISTIAN,
OF HOUSTON, TEXAS

COMBINED ELEVATOR AND WATER SEAL

Application filed July 9, 1929. Serial No. 376,996.

My invention relates to a device for raising and lowering pipe in deep wells and more particularly to devices of this character in which a seal is made between the water connections at the upper end of the well and the drill stem while the same is being lowered into or removed from the well.

In deep well drilling where gas pressures are encountered it is frequently necessary in order to prevent the escape of the gas from the well to provide for the pumping of mud or other liquid into the well while the drill stem is being removed. By so doing the pressure of the liquid upon the bottom of the hole is sufficient to keep back the gas from entering the well and gaining inertia sufficient to blow the mud or the tools from the well. It is inconvenient to connect the swivel with the joint of the drill stem each time a joint is coupled into the well or uncoupled therefrom so that circulation of fluid in the well may be kept up.

It is an object of my invention to provide a connection between the swivel and the drill stem which may be quickly made when the drill stem is elevated or moved vertically in the well so that water may be circulated into the well even when the drill stem is being removed from or introduced into the well.

I desire to provide an elevator connected with the water swivel which will be adapted for quick operation and which will make a tight seal between said swivel and said drill stem without the necessity of screwing the parts together.

I also desire to provide a device of this kind which may be conveniently operated so that the seal between the swivel and drill stem may be quickly made without the loss of a material amount of time.

The invention resides largely in the particular construction and arrangement of the parts whereby the objects as above set forth are accomplished.

Referring to the drawings herewith, Fig. 1

is a side elevation of a device embodying my invention, the invention being shown as connected to the upper joint of the drill stem.

Fig. 2 is a similar view but with the device in unlatched position ready for removal from the drill stem.

Fig. 3 is a side elevation taken at right angles to the views shown in Figs. 1 and 2 and illustrating also the connection with the swivel.

Fig. 4 is a broken side elevation similar to that shown in Fig. 3, but illustrating the device in unlatched position.

Fig. 5 is a broken longitudinal section through the joint between the drill stem and the elevator.

The drawings illustrate one embodiment of my invention and with reference to Fig. 3 it will be seen that the upper end of the drill stem 1 is adapted to be connected with the lower end 2 of the swivel 3 by means of a connecting member illustrated generally at A, and it is this connecting member which forms the subject matter of my invention.

The connecting member A comprises a tubular body 4, the upper end of which is threaded at 5 for connection with the lower end 2 of the swivel. Adjacent the lower end of the body member are two laterally projecting ears 6 having openings therein to receive pivot pins 7 upon which lever arms 8 are pivoted. Below the said ears 6 the outer diameter of the body is reduced slightly and threaded at 9 for engagement with a downwardly tapered collar 10. Below the threaded portion 9 of the body the outer diameter is still further reduced to form a shoulder 11 against which the coupling 12 upon the upper end of the drill stem 1 may contact. The space between the lower nipple 13 upon the body member and the collar 10 is sufficient to allow the insertion therein of the coupling member 12 upon the drill stem, as will be clearly understood from Fig. 5.

To form a seal about the collar 10 and the

upper end of the drill stem I provide two co-operating bushings 14, the construction of which will be understood from Fig. 4. These bushings are suspended at the lower end of arms 15 pivoted at their upper ends to brackets 16 formed upon a ring 12 clamped about the body 4 above the ears 6 and at right angles to said ears. The two bushings 14 are thus adapted to swing to and from the drill stem 1, the upper ends 17 of said bushings being adapted to engage below the coupling 12 upon the drill stem. When swung together about the drill stem the sides of the bushings contact, making a ring entirely surrounding the drill stem and bearing on the inner faces against the same.

To clamp the bushings 14 tightly about the drill stem I have provided a ring 18 adapted to surround the drill stem at a point below the upper end thereof. This ring has laterally projecting ends thereon to which links 19 are pivotally connected. Said rings 19 are pivotally connected with the lever 8 at the point 20 adjacent the inner end of said lever. The ring 18 has a downwardly tapered opening 21 therein to fit over the outer tapered surface 22 of the bushings 14. When in open position, as shown in Fig. 2, the ring 18 is immediately below said bushings but when the levers 8 are moved upwardly into the position shown in Fig. 1 the ring 18 is forced upwardly along the tapered surface 22 of the bushings and thus acts to clamp them inwardly to form a tight clamping contact with the drill stem at a point immediately below the coupling 12 thereon.

The levers 8 are adapted to be held in their upper position clamping the ring 18 against the bushing 22 by means of latching members 24. Said latching members are U-shaped pieces of wire of similar material, the inner ends of which are bent about posts 25 extending radially outwardly from the body member 4. These two outwardly extending posts or studs are of sufficient length to receive the two opposite latching members 24 and also having a coiled spring 26 thereon bearing at the outer end against a head or nut 27 upon the stud and at their inner ends against the ends of the latching members 24. The springs thus exert a frictional contact with the latch members, which tends to hold said latches in extended position, and when the said latches are engaged about the upper ends of the lever arms 8 they are received within notches 28 in the lever arms and are held in that position frictionally as will be understood.

In the use of my device, as in the removing of drill stem from the well in which gas pressure is present, the drill stem and the drill are hoisted upwardly and disconnected one section from another in the usual manner. While this operation of removing the drill stem is going on flushing fluid is pumped

downwardly into the hole to take the place of the space occupied by the drill stem. This pumping is accomplished through the type of elevator which I have provided. The bail 30 upon the swivel is engaged with the traveling block in the usual manner and connections are made between the hose from the pump and the gooseneck 31 in the usual manner so that a circulation of liquid downwardly through the swivel may be accomplished at all times.

When the device is attached to the swivel, as shown in Fig. 3, the bushing 14 is swung outwardly into the position shown in Fig. 4 and the ring 18 is lowered downwardly over the upper end of the drill stem into engagement therewith, as shown in Fig. 2. The lever arms 8 are then drawn upwardly to bring the clamping ring 18 tightly against the bushing 14 so as to clamp the same against the pipe. As will be seen from Fig. 5, there is a gasket or washer 32 between the shoulders 11 and the collar 12 of the drill stem so that a tight water seal may be obtained at that point. When the ring 18 has been clamped tightly against the drill stem, holding the coupling 12 thereon tightly in engagement with the body 4, a tight seal is made so that the circulation of the fluid downwardly from the swivel into the drill stem may be kept up while the drill stem is raised upwardly a sufficient height to expose the next joint to be uncoupled and the circulation may be kept up until the joint has been loosened.

It will be obvious that my device is adapted to operate quickly so as to make a tight connection about the drill stem and obtain a grip thereon so that the drill stem may be hoisted in the usual manner but it will also be possible to maintain a circulation during the handling of the drill stem.

The advantages of this construction lie in the fact that the coupling is quickly made as in the case of an ordinary elevator and with the additional advantage that the water circulation may be maintained during the time the pipe is being withdrawn from the well.

The further advantages of the device will be obvious to those skilled in the art.

What I claim as new is:

1. In a device of the character described a tubular body threaded at its ends, said body having a socket in its lower end to receive a coupling at the upper end of a drill stem, a divided bushing, a pair of levers pivotally connected with said body, and means connected to said levers to fit about and clamp said bushing firmly about said drill stem.

2. A combination elevator and water seal for drill stems whereby circulation thru said stem may be maintained while said stem is being moved, said elevator including a split bushing adapted to engage beneath a coupling on said drill stem, a body adapted for inser-

tion into the top of the coupling, and means to clamp said bushing and said body to said drill stem including a ring, levers on said body and links connecting said levers and

5 said ring.

3. In combination with a drill stem, an elevator therefor, means forming part of said elevator adapted to engage the drill stem to form a fluid seal, said means including a 10 split bushing to encircle the drill stem, a ring to clamp over said bushing to form the seal, and links and levers also as part of said means to actuate said ring.

In testimony whereof I hereunto affix my 15 signature this 5th day of July A. D. 1929.

WILLIAM P. DENNY.
